UNITED STATES PATENT OFFICE.

CRAWFORD L. EASTERLING, OF PLANT CITY, FLORIDA.

PLOW-STOCK.

1,107,920.

Specification of Letters Patent. Patented Aug. 18, 1914.

Application filed February 27, 1914. Serial No. 821,539.

To all whom it may concern:

Be it known that I, CRAWFORD L. EASTERLING, a citizen of the United States, residing at Plant City, in the county of Hillsboro and State of Florida, have invented new and useful Improvements in Plow-Stocks, of which the following is a specification.

This invention relates to plow stocks and it consists in the novel features hereinafter 10 described and claimed.

An object of the invention is to provide a plow stock of simple structure together with means for permitting the standard to be adjusted with relation to the beam and means 15 for effectually holding the standard at an adjusted position which means does not include threaded bolts and nuts which are objectionable for the reason that the said parts when rusted are difficult to manipulate.

20 With the above object in view the invention consists of U-shaped members attached to the opposite sides of the beam, and front and rear standards pivotally connected with the said U-shaped members. A bar connects 25 the lower ends of the front and rear standards together and a bar connects the intermediate portions of the said standards together. A key bolt is adapted to be passed through the intermediate portions of the 30 said U-shaped members and through the uppermost bar and serves as means for holding the parts in proper position.

The accompanying drawing: Figure 1 is 35 a perspective view of the plow stock. Fig. 2 is a side elevation of parts of the stock with portions broken away.

The stock comprises a beam 1 upon which is mounted handles 2 in any suitable manner. Approximately U-shaped members 3 40 are secured at their ends to the opposite sides of the beam 1 and are provided at their lower intermediate portions with openings 4. A standard 5 is pivotally connected at its upper end with the forward end portions of the U-shaped members 3 and a standard 6 is similarly attached with the rear end portions of the said U-shaped members. A bar 7 is pivotally connected at its forward end with the lower portions of the standard 5 and is pivotally connected at its rear end with the lower end portion of the standard 6. A bar 8 is pivotally connected

at its forward end with the intermediate portion of the forward standard 5 and is pivotally connected at its rear end with the intermediate portion of the rear standard 6. The intermediate portion of the bar 8 passes between the U-shaped members 3 located at the opposite sides of the beam. The bar 8 is provided at its intermediate portion with a series of openings 9 any one of which may be brought into register or alignment with the openings 4 in the intermediate portions of U-shaped members 3. A key bolt 10 is adapted to be passed transversely through the openings 4 and any one of the openings 9 which may be in register with the same and the said key bolt is secured in the said opening by means of a cotter pin 11 which is passed transversely through the said bolt 60 in the usual manner and positioned therein the ends thereof are spread. Therefore it will be seen that the standards 5 and 6 may be readily adjusted with relation to the beam 1 by removing the key bolt 10 from the openings 4 and 9 and swinging the said standards whereby the bar 8 is moved longitudinally between the intermediate portions of the U-shaped members 3. When the parts are at the desired positions the key bolt 10 is re- 70 inserted in the openings 4 and 9 and consequently the parts are securely held at the adjusted positions.

Having described the invention what is claimed is:

1. A plow stock comprising a beam, approximately U-shaped members attached to the opposite sides of the beam and provided at their intermediate portions with openings, standards pivotally mounted at the forward 90 and rear ends of the said U-shaped members, a bar connecting the lower portions of the standards together, a bar connecting the intermediate portions of the standards together and lying between the intermediate 95 portions of the U-shaped members, and provided with a series of openings and a securing device passing transversely through the U-shaped members and the last mentioned bar.

2. A plow stock comprising a beam, approximately U-shaped members secured to the opposite sides of the beam and provided at points between the ends with openings,

standards pivotally secured to the U-shaped members at the forward and rear ends thereof, bars connecting the lower portions of the standards together, one of the bars lying between the U-shaped members and being provided with a series of openings, and a key bolt passing transversely through the members and the bar which is located between

the members and a securing device passing through the bolt. 10

In testimony whereof I affix my signature in presence of two witnesses.

CRAWFORD L. EASTERLING.
